UNITED STATES PATENT OFFICE.

BURT STANLEY MINOR, OF LOS ANGELES, CALIFORNIA, ASSIGNOR TO REGAN FORGE & ENGINEERING COMPANY, OF SAN PEDRO, CALIFORNIA, A CORPORATION OF CALIFORNIA.

DEFLECTOR FOR SHEAVE BLOCKS.

Application filed April 14, 1924. Serial No. 706,323.

To all whom it may concern:

Be it known that I, BURT STANLEY MINOR, a citizen of the United States, residing at Los Angeles, in the county of Los Angeles 5 and State of California, have invented a new and useful Deflector for Sheave Blocks, of which the following is a specification.

My invention relates to a deflector for sheave blocks and particularly to sheave 10 blocks employed in connection with oil well derricks.

Heretofore in lifting casing, and similar structures in oil well derricks, the sheave block connected to the upper end of the 15 casing sections often accidentally contacts in its vertical movement with the "finger board" or other portions of the derrick structure, resulting in damage thereto.

The main object of my invention is to 20 provide deflectors for sheave blocks which will effectually deflect the block past the "finger board", and other stationary objects during its operating movements, whereby injury to the "finger board" derrick structure 25 will be obviated.

Other objects and advantages will be clearly apparent from the following description, reference being had to the accompanying drawing forming a part thereof, in 30 which:

Fig. 1 is a front elevation of a sheave block and the deflector attached thereto.

Fig. 2 is a side view of the deflector and the upper portion of the block to which the 35 deflector is attached.

Fig. 3 is a vertical longitudinal section of the deflector taken on line 3—3 of Fig. 2.

Fig. 4 is a horizontal section of the deflector taken on line 4—4 of Fig. 3.

40 In the drawing 10 designates a sheave block similar to my improved block illustrated and described in my co-pending application for patent entitled "Sheave block", bearing Serial No. 649,244, filed July 3, 1923, 45 the block consisting of a plurality of inner and outer straps 11 and 11' respectively, suitably spaced apart by separators, sheaves 12 being journaled in bearings secured to the various straps. Pivotedly mounted on a bolt 50 14 is a lower clevis 13, the upper clevis 15 being pivotally connected to the bolt 16 that passes through the upper end of the sheave straps.

55 The deflectors which preferably consist of plates 20 are secured to the upper and lower

ends of one of the outside straps 11', by the bolts 14, 16, their free ends 21 extending beyond the ends of the strap 11', and are bent or curved inwardly towards the upper and lower clevises. The upper side edges 60 of the plates converge upwardly and terminate in a rounded end 22. Vertical reinforcing and deflecting beads 23 are formed externally along the vertical side edges of the plates 20 to a point 24 on the free ends 65 of the plates. Plates 20 are provided with bolt holes 25 in their lower portions through which the bolts 14 and 16 extend with the heads 26 of the bolts engaging the outside 70 of the plate, holding them firmly against the upper and lower ends of the outer strap 11' to which the plate is attached. Inwardly extending lugs 27 are provided on the lower side edges of the plates 20 which engage notches 28 formed in the upper and lower 75 edges of the straps 11', to which the plate is attached, whereby the deflector is properly centered on said bar and held against shifting thereon. The upper clevis 15 is of small size and its ends 29 pivotally engage bolt 80 16 between the upper ends of the inner straps 11.

When the block is raised in the derrick and approaches the finger board in the upper part of the derrick, the upper arched portion 21 of the deflector first engages the "finger board" and diverts the block to one side, and then the beads 23 engage the "fingerboard" and deflect the block past the same, the beads 23 extending slightly outside 90 the bolt head 16 so that the "finger board" will escape said head, thus preventing breaking of the "finger board" or injury thereto.

While the guards are illustrated as attached to only one side of the sheave block, 95 it will be understood that they may be mounted on the other side of the block as shown in dotted lines in Fig. 1, the nuts 17 holding the guards firmly in position.

100 What I claim is:

1. A deflector for sheave blocks, comprising a flat metallic member adapted to be secured to the outer surface of one of the side frame portions of a sheave block, the upper end of said member being bent transversely, 105 and means formed on said member and engaging the sheave frame to prevent a shifting movement after the same has been secured to said block.

2. A deflector for sheave blocks, comprising 110

ing a metal deflecting member adapted to be secured to one of the side frames of a sheave block, the upper end of said member being bent transversely, and lugs formed on the lower end of said member and engaging recesses formed in the side frame of the block for preventing a shifting move-

ment of the deflector when secured in position.

In witness that I claim the foregoing I have hereunto subscribed my name this 8th day of March, 1924.

BURT STANLEY MINOR.
